UNITED STATES PATENT OFFICE.

GEORGE H. CUMMINGS, OF WATERBURY, CONNECTICUT.

INSTEP-SUPPORT.

No. 808,515.

Specification of Letters Patent.

Patented Dec. 26, 1905.

Application filed November 22, 1904. Serial No. 233,912.

To all whom it may concern:

Be it known that I, GEORGE H. CUMMINGS, a citizen of the United States, residing at Waterbury, in the county of New Haven and 5 State of Connecticut, have invented a new and useful Instep-Support, of which the following is a specification.

This invention relates to instep-supports.

The object of the invention is to provide 10 an instep-support which will be thoroughly comfortable in use, in which the arch-plate or instep-support proper will readily yield to pressure, thus to obviate discomfort, and which may readily be manufactured and sold 15 at a price to place it within the reach of all desired users.

With the above and other objects in view the invention consists in the various novel 20 details of construction of an instep-supporter, as will be hereinafter fully described and claimed.

In the accompanying drawings, forming a 25 part of this specification, and in which like characters of reference indicate corresponding parts, Figure 1 is a view in perspective of an instep-supporter constructed in accordance with the present invention viewed from the under side. Fig. 2 is a perspective view viewed from the upper side, a portion of the 30 sheathing of the structure being removed to exhibit the manner in which the arch-plate is combined with the base-plate. Fig. 3 is a view in transverse section taken on the line 33, Fig. 2.

Referring to the drawings, 1 designates the 35 base-plate, which may be made of any suitable material, preferably of spring metal; 2, the arch-plate, which is also made of spring metal; and 3 the sheathing or covering, 40 which may be of any suitable material, preferably of leather. The base-plate is appropriately shaped to fit within the heel and instep portions of a shoe, and its under side is devoid of a covering; but the upper side, as 45 also the arch-plate 2, is covered by the sheathing 3, above referred to, which is combined with the base-plate through the medium of eyelets 4 and with the arch-plate by rivets 5, although, if preferred, these latter 50 may be also eyelets. In order to prevent the sheathing from creeping or slipping upon the

base-plate and arch-plate, it may be cemented thereto, preferably by means of black japan or asphaltum, these being impervious to the action of moisture, which will be necessary in order to render the device thoroughly effective in use. The arch-plate is approximately triangular in form and has its terminals 6 and 7 rounded, the intermediate portion of the plate being bowed or arched to 60 conform to the under side or instep portion of the foot. The arch-plate is secured to the base-plate by rivets 8, which pass through the terminal 7 and through the base-plate, as clearly shown in Figs. 2 and 3. 65

As clearly shown in Fig. 2, the terminals 6 are adapted to slide or work upon the base-plate and with the pressure of the weight of the wearer, and this will positively preclude any discomfort in use or tiring of the foot, 70 which would inevitably result if there were no yield to the arch-plate.

The device as a whole is exceedingly simple of construction and may readily be manufactured without the employment of special 75 machinery for the purpose. The base and arch plates will preferably be made of a non-oxidizable metal, such as spring-brass, whereby the life of the article is rendered practically limitless, the only part that can be deteriorated with age being the sheathing, and this may readily be replaced when worn out. 80

Having thus described the invention, what is claimed is—

1. An instep-supporter comprising a base-plate and an inherently-resilient arch-plate 85 rigidly secured to the base-plate at one side only, the arch-plate being shaped on the proper curved lines to impart the natural bow to the instep. 90

2. An instep-supporter comprising a resilient base-plate, and a resilient upwardly-curved arch-plate rigidly secured to the base-plate at one point only.

In testimony that I claim the foregoing as 95 my own I have hereto affixed my signature in the presence of two witnesses.

GEORGE H. CUMMINGS.
